UNITED STATES PATENT OFFICE.

GEORGE W. AURINGER, OF NEW ROCKFORD, NORTH DAKOTA.

IGNITING DEVICE.

1,086,697.

Specification of Letters Patent. Patented Feb. 10, 1914.

Application filed May 3, 1913. Serial No. 765,304.

To all whom it may concern:

Be it known that I, GEORGE W. AURINGER, a citizen of the United States, residing at New Rockford, in the county of Eddy and State of North Dakota, have invented new and useful Improvements in Igniting Devices, of which the following is a specification.

This invention relates to improvements in igniting devices and has particular application to a gas igniting device.

In carrying out the present invention, it is my purpose to provide a device of the class described which may be readily attached to a gas burner and removed therefrom and which when in applied position will be connected up with the controlling valve or gas cock in such manner that when the latter is actuated to open position the igniting device will be operated to ignite the gas issuing from the burner or tip as the case may be.

It is also my purpose to provide a device of the class described which will embrace the desired features of simplicity, efficiency and durability coupled with cheapness of cost in manufacture and marketing and which may be readily and conveniently installed and maintained at a minimum expense.

With the above and other objects in view, the invention consists in the construction, combination and arrangement of parts hereinafter set forth in and falling within the scope of the claim.

In the accompanying drawing; Figure 1 is a view in side elevation of a gas burner equipped with the present invention. Fig. 2 is a top plan view thereof, and Fig. 3 is a view in end elevation of the abrading member.

Referring now to the accompanying drawing in detail, the numeral 1 designates a gas burner of any approved or well known construction, while 2 indicates the controlling valve or cut off cock by means of which the flow of gas to the tip of the burner is regulated and controlled. In the present instance, the stem of the controlling valve 2 is equipped with a cross arm 3 to the free extremities of which are fastened chains 4 depending from the cross arm and terminating in finger rings 5. By means of this construction, it will be seen that when one

chain 4 is pulled in a downward direction, 55 the cross arm 3 will be swung so as to throw the controlling valve to open position, while when the other chain is moved downwardly, the cross arm will be actuated to move the valve to closed position. 60

In the embodiment of my invention selected for illustrative purposes, my improved igniting device embodies a spark producing block 6 suitably secured to a band 7 encircling the tip end of the burner 1, and 65 a lever 8 fulcrumed between its ends upon a stud 9 carried by a band 10 surrounding the burner tube 1 below the band 7, the bands 7 and 10 being preferably split and each having the confronting ends thereof 70 outturned to form lugs adapted to receive a set screw 11 whereby the respective band may be clamped upon the tube.

Pivotedly connected to one end of the lever 8, that is, the outer end of such lever, is a 75 link 12 having the lower extremity thereof pivotally connected as at 14 to one end of the cross arm 3, while formed in the free end of the lever 8, that is, the inner end of the lever, is a diagonal slot 15 in which is 80 seated a spring-like abrading element 16 having the relatively high edge thereof contacting with the spark producing block 6 so that when the abrading element is moved upwardly over the block sparks will be 85 emitted by the latter, while in the downward movement of the abrading element such element will idle over the block and thereby eliminate waste.

From the foregoing description taken in 90 connection with the accompanying drawing, the construction, mode of operation and manner of employing my invention will be readily apparent. In the downward movement of the respective chain 4 to open the 95 valve, the link 12 moves downwardly and so swings the lever 8 about the stud 9 thereby elevating the inner end of the lever. As the inner end of the lever 8 moves upwardly, the respective edge of the abrading element 100 16 rides over the spark producing block 6 and so causes the latter to emit sparks with the effect to ignite the gas issuing from the burner tube. On the other hand, when the other chain 4 is pulled so as to cut off the 105 supply of gas to the burner, the abrading element 16 idles over the spark producing block 6 in the downward movement of the

inner end of the lever 8 under the action of the link 12, thereby prolonging the life of the spark producing block.

I claim:

5 The combination with a gas burner, a controlling valve therefor, and means for operating said valve, of an igniting device comprising a spark producing block, connections between said block and burner, a
10 pivot stud, a connection between said stud and burner; a lever fulcrumed between its ends upon said stud and having one end thereof terminating adjacent to said spark producing block and formed with a diagonal slot, a flat spring-like abrading element

seated within said slot and disposed at an angle to said block and adapted when moved thereover in an upward direction to cause the production of sparks, and when moved in the reverse direction, to idle over the 20 block, and a link connection between said valve operating means and the free end of said lever whereby in the movement of the valve the sparking device will be operated.

In testimony whereof I affix my signature 25 in presence of two witnesses.

GEORGE W. AURINGER.
